United States Patent Office.

CONRAD FURST, OF CHICAGO, ILLINOIS.

Letters Patent No. 96,575, dated November 9, 1869.

IMPROVEMENT IN COULTERS FOR PLOWS.

The Schedule referred to in these Letters Patent and making part of the same.

To all whom it may concern:

Be it known that I, CONRAD FURST, of the city of Chicago, in the county of Cook, and State of Illinois, have invented certain new and useful Improvements in Coulters for Plows; and I do hereby declare that the following is a full, clear, and exact description thereof, reference being had to the accompanying drawings, making a part of this specification, in which—

Figure 1 represents a top view,

Figure 2, a side view,

Figure 3, a top view, showing change of position from the plow-beam, and

Figure 4, a similar view, showing change toward the beam.

My improvements relate to that class of coulters which is usually called "caster-rolling coulters;" and consists in providing an arm or pendant, having a curved or angular back, with a side cylindrical bearing, to receive the shaft of a fork or arms, which hold the coulter-wheel, so that by reason of such side bearing and the curved or angular back of the pendant, the position of the coulter, relative to the plow, may be easily changed, and adapted to the plow, by bringing the coulter nearer to the plow-beam, or by carrying it further off, in providing the bottom of such side bearing with a stop, to limit the movements of the coulter-wheel, and in the several combinations hereinafter set forth and claimed as new.

To enable others skilled in the art to make and use my improvements, I will describe their construction and operation.

A represents a section of the beam of any ordinary plow.

B represents an arm or pendant, attached thereto by a clamp or clip, F G, on the landside.

This arm or pendant is usually cast, but may be made of plate-metal, or other suitable material, and has its side next to the beam convex, as shown, or it may have a ridge in the middle, or be made angular on the back, if desired.

The bearing C is usually made a part of the arm B, and located at the side thereof, as shown.

The shaft H of the fork E, passes through this bearing, and is held in place by means of a pin and a cap or washer, c, at the top.

The shaft H is bent at an angle of about forty-five degrees with the fork E, as shown, and the coulter-wheel D, which is supported by said fork, is made thin and sharp, in the usual manner.

At the lower end of the bearing C, a notch or opening, b, is made deep enough to receive the stop or pin a, and extends about one-fourth of the distance around the bearing, as shown.

The advantages of locating the stop at the bottom

or lower end of the cylinder or bearing are, that the top can be closed by a close-fitting cap, or washer, so as to keep the dirt out of it; and as there is a tendency to twist the shank H, or considerable torsion applied to it, by reason of the angle of the fork E, the shank can be made much lighter when the stop is placed at the bottom than it can be when placed at the top, as the stop is located at or near the point of the strain.

I am aware that the upper ends of straight shanks or forks, holding the wheel, in coulters which were not of the caster or swivel kind, have heretofore been provided with a curved back, so as to change the course of the coulter, and thereby guide the plow so that it will cut a wider or narrower furrow; but this old device does not and cannot change the position of the coulter-wheel, so as to bring it toward or carry it from the plow, for the reason that the axis of the coulter-wheel is always in the same place, and turning such shank only changes the direction of the wheel, without changing the position, while in my device the coulter-wheel does not and cannot act as a guide to the plow, as it turns freely on the shaft H, and changing by the curved arm or pendant simply changes the position, without altering the direction of the wheel.

Plows, as made by different manufacturers, have a considerable variation in the setting of the beams with reference to the landside of the plow, making it necessary, in order to adjust the coulter to these variations, to devise some means to set it closer to or further from the beam, so as to bring it in the line of the plow.

By the old way, even with a curved back to the coulter-shank, it is necessary to carry the coulter out by means of wedges driven between it and the plow-beam. The use of wedges, which are inconvenient and uncertain, is avoided by my invention, and a ready and certain means for adjustment furnished, for by letting out the screw-nut d of the clip or clamp, and screwing down e, as shown at fig. 3, the coulter is carried from the beam, and by reversing the movement of these screws, it is drawn toward the beam, as shown at fig. 4, and thereby adjusted to the location or angle of the beam to which it is attached.

It will readily be seen, that these results are obtained by placing the bearing C on the side of the pendant or arm B, in connection with the curved or angular back thereof, and the clamp.

The clamp is made of a bent bar, F, and a cross-bar, G, connected by the screws d and e, and is attached to the beam of a plow, as shown.

Having thus fully described my invention, what I claim as new, and desire to secure by Letters Patent, is—

1. The arm, or pendant B, having a curved or angular back, and a cylinder or bearing, C, on the side thereof, in combination with a bent fork, E H, substantially as and for the purposes specified.

2. The combination and arrangement of the adjustable clamp F G, with the beam A, arm B, when provided with a curved or angular back, and a side

bearing, C, stop *a b*, bent wheel-fork E, and wheel D, all constructed and operating substantially as specified.

CONRAD FURST.
